UNITED STATES PATENT OFFICE.

ANTHONY M. ZOTTOLI, OF QUINCY, MASSACHUSETTS.

PAVING BLOCK.

Application filed June 21, 1923. Serial No. 646,798.

This invention relates to a new and useful improvement in paving blocks. Paving blocks as usually constructed and laid have a tendency to settle more or less unevenly, owing to heavy traffic or uneven settling of the bed in which the blocks are laid, or some other causes, so that frequently one of the blocks will be settled more than an adjacent block, thereby creating numerous depressions in the pavement, so that the pavement becomes uneven and occasions jolting of the vehicles. Furthermore, after the irregular settling of the blocks in this way, they are more liable to become broken than if the surface were maintained uniform. There is also a tendency of the blocks to be separated from each other, both laterally and longitudinally of the travelled way more than is intended by the thin spacing which is left in the original pavement. This produces spaces which are not filled by the sand or cement in which the blocks are originally laid and renders the blocks more likely to be crumbled or broken.

The object of the present invention is to provide such a construction of paving block that the blocks when laid and chinked with cement will have an interlock of the cement in such manner as to prevent sliding, creeping or settling of the blocks.

The invention will be fully understood from the following description when taken in connection with the accompanying drawings, and the novel features thereof will be pointed out and clearly defined in the claims at the close of this specification.

In the drawings:

Fig. 1 is a perspective view of a paving block embodying the invention.

Fig. 2 is a transverse vertical section of one of the blocks.

Fig. 3 is a horizontal section.

Fig. 4 is a horizontal sectional view of a section of pavement laid up with blocks embodying the invention.

Fig. 5 is a section on line 5—5, Fig. 4.

Fig. 6 is a horizontal sectional view of a modified form of block.

Referring now to the drawings, there is shown at 1 a paving block embodying the invention, which is preferably molded and made of concrete or cement, or other suitable material of which molded paving blocks are made. The block is of rectangular form and molded in such manner that it is formed with a recess 2 in each of its two vertical

sides and with a recess 3 in each of its two ends. The upper or tread face and the lower face are preferably unrecessed. The purpose of the recesses 2 and 3 in the vertical sides and ends is to receive the gobs 4 of cement when the blocks are laid in the pavement and the cement is poured in through the crevices between the blocks, so that there will be fins 5 of cement filling the crevices, the fins being connected with the gobs which fill the recesses.

When the blocks are molded, there are embedded in the block two rods 6 and 7, the rod 6 extending longitudinally through the block, and the rod 7 extending transversely through the block, the rod 6 projecting through the end recesses 3 and preferably for a short distance beyond the plane of the end face of the block, and the rod 7 extending through the recesses 2 in the side faces of the block and also projecting preferably for a short distance beyond the plane of the side face of the block. Preferably the longitudinal rods 6 are formed with a bent 80 outer end portion 8 at each end and the transverse rods 7 are formed with a bend 9 at their outer ends. Preferably these rods are made of stiff wire.

When the blocks are laid, as shown in Fig. 4, with thin spaces between them, the cement will be poured in, filling up the spaces between the blocks and the recesses 2 and 3 in the sides and ends of each block, forming gobs 4 which extend from the interior of the recess in one block to the interior of the recess in the adjacent block, the gobs having fins 5 which fill the thin spaces between the blocks. This, of itself, has some effect in preventing the settling of one block with 95 relation to another and also of the creeping of one block with relation to another, but under heavy traffic the pressure of a heavy load on any one of the blocks which is not equally applied to the adjacent block frequently breaks this gob of cement between the two adjacent blocks. By reason of the rods which project from all the vertical sides of the blocks and are embedded in the cement, there is provided a reenforce to the cement which enables the blocks to stand a much greater strain longitudinally, laterally and vertically. The straight projecting portions 6, 7 of the rods aid materially in tying the several blocks together, but by forming the rods with the bends at the ends, the strength is greatly increased.

The straight, outwardly extending portions 7 of the transverse rods and the bent end portions 8 of the longitudinal rods all act against the line of pressure or thrust and thereby aid in preventing longitudinal displacement or creeping of the blocks. The straight, outwardly extending portions 6 of the longitudinal rods which extend at right angles to the face of the block, and the bent 10 ends 9 of the transverse rods which lie at right angles with the end faces of the blocks resist lateral thrust or movement of the blocks, and the entire protruding portions of all of the rods resist the sagging of the 15 blocks.

In the modification shown in Figure 5, the longitudinal rods 11 and the transverse rods 12 are both shown as extending through the block and projecting from the faces 20 thereof at an acute angle to the sides and ends of the block without being bent. In this form of construction, the projecting rods all extend at an angle to the line of pressure longitudinally, laterally, and down- 25 wardly.

While the rods are shown as being continuous entirely through the block, this is not essential, the important feature being that there shall be a protruding portion and 30 an embedded portion of sufficient length to be anchored firmly in the block.

The rods are preferably made of iron but may be made of any other suitable material.

What I claim is:

35 1. A rectangular paving block having a recess in each of its vertical sides, each recess being entirely within the margin of the outer side face of the block and bordered all around by a flush portion of the side 40 face, and rods embedded in the block which respectively extend longitudinally and transversely entirely through the block and project outwardly through said recessed portions beyond the plane of the side face of 45 the block, and having hook like ends.

50 2. A pavement composed of blocks each having recesses in its four vertical faces, each of said recesses being entirely within the margin of the respective face and sur- rounded by a marginal portion flush with

the outer face of the block, and rods secured in said blocks which respectively extend longitudinally and transversely entirely through the block and project out through the said recesses in the sides beyond the outer 55 face of the block, said blocks being laid with thin spaces between them, said spaces being filled with cementitious material which fills said recesses and the crevices between the blocks and embeds the projecting portions 60 of the rods therein.

3. A pavement composed of blocks having recesses in their vertical faces, each of said recesses being entirely within the margin of the respective face and surrounded by a 65 marginal portion flush with the outer face of the block, and rods secured in said blocks which respectively project out through the said recesses in the sides beyond the outer face of the block, said blocks being laid with thin spaces between them, and with the rods 70 of each block projecting into the recesses in the sides of the adjacent blocks, said spaces and recesses being filled with cementitious material which embeds the projecting portions 75 of the rods therein.

4. A pavement composed of blocks having recesses in both sides and ends, each of said recesses being intermediate the edges thereof and entirely within the margin of the respective faces and surrounded by a marginal portion flush with the outer face of the block, and rods secured in said blocks which respectively extend longitudinally and transversely through the block and project out through the said recesses in the sides beyond the outer face of the block, said blocks being laid so that each recess in any block will face a recess in an adjacent block and form there- 80 with a combination pocket, and with the rods of each block projecting into the recesses in the sides of the adjacent block and cementitious material which fills said recesses and embeds the projecting portions of the rods 85 therein, the rods in each block lapping past the rods in the adjacent block and being formed with bends at the ends which are 90 embedded in the cement.

In testimony whereof I affix my signature.
ANTHONY M. ZOTTOLI.
